UNITED STATES PATENT OFFICE

148,327

DESIGN FOR A ONE-WHEEL TRAILER

Melvin J. Rasbach, Wichita, Kans.

Application November 21, 1946, Serial No. 134,993

Term of patent 14 years

(Cl. D14—3)

To all whom it may concern:

Be it known that I, Melvin J. Rasbach, a citizen of the United States, residing at Wichita, in the county of Sedgwick and State of Kansas, have invented a new, original, and ornamental Design for a One-Wheel Trailer, of which the following is a specification, reference being had to the accompanying drawing, forming part thereof, in which

Fig. 1 of the drawing is a plan view of a one-wheel trailer embodying my new design,

Fig. 2 of the drawing is a side elevation of the trailer shown in Fig. 1, and

Fig. 3 of the drawing is a rear elevation of the trailer shown in Fig. 1.

I claim:

The ornamental design for a one-wheel trailer, substantially as shown.

MELVIN J. RASBACH.
